UNITED STATES PATENT OFFICE.

JOHN G. GOSELIN, OF HYDEPARK, MASSACHUSETTS.

TYPE-SETTER'S MACHINE.

No. 811,285.

Specification of Letters Patent.

Patented Jan. 30, 1906.

Application filed August 4, 1904. Serial No. 219,481.

To all whom it may concern:

Be it known that I, JOHN G. GOSELIN, a citizen of the United States, residing at Hyde-park, in the county of Norfolk, in the Commonwealth of Massachusetts, have invented 5 an Improvement in Type-Setters' Machines, of which the following description, in connection with the accompanying drawings, is a specification, like characters on the drawings 10 representing like parts.

This invention relates to machines or mechanisms for automatically presenting printing-type in a convenient position to be selected for setting by a compositor as rapidly 15 as may be necessary to supply the needs of compositors of the highest degree of skill, and, further, contemplates the presentation of the different letters of a font of type arranged relatively in a manner familiar to the great 20 majority of compositors, the aim of the invention being to facilitate rapid setting of the type by hand.

The character and scope of the invention and also the advantages arising therefrom 25 will be clearly apparent from a description of one embodiment thereof illustrated in the accompanying drawings, in which—

Figure 1 is a side elevation of the complete machine, some of the working parts being 30 shown in dotted outline. Fig. 2 is a top plan view. Fig. 3 is a front elevation. Figs. 4 and 5 are vertical sectional views from front to rear, showing different positions of the type-moving mechanism. Figs. 6, 7, and 8 35 illustrate details of parts shown in Figs. 4 and 5.

In the embodiment of the invention herein selected for illustration the machine consists of a plurality of magazines or type-supplying 40 means 1, suitably mounted substantially in a vertical position upon a base 2 and extending in a bank transversely of the machine and consisting in this instance of side and back walls, forming channels of a size and shape to 45 hold the type in columns when lying broad-side one upon the other, the channels being open at the front to permit an operator readily to observe the condition of the supply of type therein. Projecting from the front of 50 the type-magazines are a plurality of guides, one for each magazine, to transfer the type to convenient points to be selected by an operator, said points being in a given plane, preferably inclined at an angle to the horizontal to 55 correspond to the inclination at which a

printer's type-case is ordinarily positioned. The terminal points of these channels, furthermore, are preferably arranged relatively to correspond to the relative positions of the compartments of a printer's case, so that the 60 appropriate type may be presented for the selection in an arrangement familiar to the great majority of compositors. In order to present even a more familiar aspect to the 65 compositor, and thus assist him in the rapid selection of the required type, the terminals of the type-guides may be provided with a suitable face-plate 4, the surface of which may be divided in any suitable manner by division marks or ledges to represent the divisions of an ordinary type-case. In the present instance these divisions are formed by a plurality of ledges or shelves 5, and the face-plate 4 is further provided with a plurality of 70 apertures 6, at least one for each division 75 thereof, and alined with the terminals of the type-guides 3, through which the type may be projected and rest upon the ledges 5 in a convenient position for selection. The divisions for the more commonly used type, however, may be provided with more than one aperture. In order that the type may be readily supplied at the apertures or points 6, the magazines 1, as herein shown, have their bases located at corresponding levels and in 80 corresponding arrangement relative to said points, although my invention is not limited to any particular arrangement of the magazines with reference to these points.

Any suitable means may be employed to 90 transfer the type from the magazines to the points 6; but as herein shown such means consists of a plurality of type-pushers 7, one for each magazine, which are slidably mounted in guides 8, projecting from the rear of 95 said magazines and located in alinement with the corresponding type-guides 3. These pushers, Fig. 6, each consists of a body portion 9, which rests upon ledges 10, Fig. 8, extending longitudinally of the guide 8 through 100 the magazine 1 and also longitudinally of the guide 3, thus forming a base for the guides to support the type *a* as well as the pusher 7. Depending from the body portion 9 of each 105 pusher 7 and between the ledges 10 is a plate 11, having its rear end 12 formed to receive the correspondingly-shaped end 13 of the pusher-actuator 14, the latter being pivoted or otherwise suitably connected at 15, Fig. 1, to an actuating-plate 16, which in turn is 110

slidably mounted in guides 17, extending from the base-plate 2 of the machine and actuated through suitable connecting-rods 18, extending from a disk 19, mounted on a power-5 shaft 20 at the rear of the machine.

In order to retract the pusher 7 after a type has been moved to the selecting-point 6 and to position the pusher in readiness to actuate another type, a pusher-retractor 21 is 10 provided, also attached to the actuator-plate 16 and having at its forward end a depending lug 22, adapted to engage a lug 23, projecting up from the rear end of the pusher 7.

15 As shown in Fig. 1, a set of pushers, pusher actuators, and retractors is provided for the respective type - magazines 1, so arranged that type will be simultaneously moved from each of said magazines to the corresponding 20 points 6 at the terminals of the guides 3. In the operation of setting type, however, some letters will be selected much oftener than others, thus leaving the remaining type at the 25 points 6 during successive operative movements of the type-actuating mechanism. In order, therefore, under these circumstances to prevent more type being moved to the selecting-points already occupied, and thus forcing the type at these points out of the 30 machine, I have provided such actuator with an actuator-controller 25, pivoted at 25^a at the rear end of the guide 8 and having its forward extremity shaped to extend up through the guide 3 and across the path of the type 35 therein, the said extremity being normally held in elevated position in any suitable manner, as by a spring 27 at the rear end of the lever. When a type is withdrawn from its position at point 6, the controller is permitted 40 to rise into the upper position, (indicated in dotted outline in Fig. 5,) in which position a lug or projecting portion 26 thereon, against which the pusher-actuator is held by the spring 29, supports said actuator in operative 45 position relatively to pusher 7 to enable the latter to push a new type into position. When, however, the next type is pushed into 50 position at 6, the controller is held depressed by said type, as shown in Fig. 4, and the actuator 14 is permitted to drop below the path of the pusher 7 and thereafter hence plays idly in the lower part of the guide 8 until said type is withdrawn.

A description of the operation of a single 55 set of the type-actuating mechanism will suffice for all. The magazines having been supplied with appropriate type, the mechanism is set in motion from a convenient source of power through a belt 30 on a pulley 31, mounted upon the power-shaft 20, whereby 60 rapid reciprocation is imparted to the actuator-plate 16 and the pusher-actuator plate 14 and retractor 21, connected therewith. There being initially no type at the point 6, 65 the forward extremity of the controller 25

assumes its elevated position, throwing the pusher-actuator 14 into operative position in alignment with the pusher 7, whereupon the actuator upon its forward movement engages the pusher 7 and upon further movement 70 causes the latter to move a piece of type from the magazine 1 along the guide 3. During this forward movement of the pusher 7 a projection 32 on the depending plate 11 thereof engages a cam-surface 33 on the controller 25, Fig. 5, and depresses the latter to permit further movement of the type to the point 6, where it overlies said controller to hold the latter depressed. Upon the return stroke of the actuating mechanism the controller in 80 this position permits the pusher-actuator 14 to drop out of engagement with the pusher 7 down upon the projection 26 of said controller. At the same time the retractor in moving to the rear engages the lug 23 of the 85 pusher 7 and moves the latter back to initial position. If before the next forward stroke of the mechanism the type at 6 has been removed, the controller will have been thereby permitted to rise to its elevated position and 90 the operation for pushing forward a new type will be the same as before. If, however, such type remains at the point 6, the controller 25 will be retained in depressed position 95 thereby. Hence the pusher-actuator will play idly in its lower position out of engagement with the pusher.

To prevent type at the point 6 from being accidentally pushed back along the guide 3, the forward end of the controller 25 is provided with a shoulder 34, which stands behind the rear end of the type when lying at the point 6. In the particular construction herein shown the guides 3 are made of different lengths to correspond with the inclination 105 of the plane of the terminals thereof or of the face-plate 4. It is therefore evident that the pushers in the lower guides 8 will have a greater distance to traverse than those in the upper guides in moving the type from the 110 magazines to the selecting-points. In order to provide for this difference in the length of stroke of the different pushers, the engaging 115 points 12 thereon are located at correspondingly-different distances from the rear ends of the body portions 9 of the pushers, so that the pusher-actuators 14 in the upper banks of guides will move forward for some distance, idly, before engaging the pushers and imparting forward movement thereto, whereas in 120 the lower banks of guides the distance which the actuators 14 move to the rear of the engaging points 12 of the pushers is only sufficient to permit of the disengagement of these parts in order that the actuators may drop down 125 upon the projections 26 of the controllers 25 when it is necessary that the actuators shall operate idly. Thus my invention provides not only for presenting type in the most advantageous position to be grasped in the op- 130

eration of type-setting, but also for arranging the type in a manner familiar to a type-setter, whereby the operation of setting-type is greatly facilitated and the speed of the operator correspondingly increased.

While the mechanism here described has been found in practice to operate satisfactorily, it is to be understood that the same is herein selected merely as one embodiment of the invention, and the latter is in no sense limited thereto; but many changes may be made in the construction and relative arrangement of the parts without departing from the spirit and scope of the invention.

15 I claim—

1. In a type-setter's machine, the combination with type-supplying means and means for maintaining type at points in the same relative positions as the divisions of a printer's case, of means for moving type from said supplying means to said points.

2. In a type-setter's machine, the combination with type-supplying means and a face-plate, having indicated thereon the divisions of a printer's case, of means for presenting the appropriate type within said divisions.

3. In a type-setter's machine, the combination with type-supplying means of a face-plate provided with ledges dividing said plate according to the divisions of a printer's case, and means to deposit the appropriate type within said divisions and upon said ledges.

4. In a type-setter's machine, the combination with a plurality of type-magazines and means for maintaining the type at a plurality of presentation-points arranged at different levels in an inclined plane, of guides connecting said magazines and points, and means controlled by the presence of type in said guides for moving type from said magazines to said points.

5. In a type-setter's machine, the combination with a plurality of type-magazines, and means for maintaining the type at a plurality of presentation-points arranged at different levels in an inclined plane, of guides connecting said magazines and points and means controlled by the presence of type at said presentation-points for moving the type from said magazines to said points.

6. In a type-setter's machine, the combination with a plurality of type-magazines and means for maintaining the type at a plurality of presentation-points arranged at different levels in an inclined plane, of guides connecting said magazines and points and means controlled by the type for moving type from said magazines to said points.

60 7. In a type-setter's machine, the combination with a plurality of type-magazines and means for maintaining the type at a plurality of presentation-points arranged at different levels in an inclined plane, of guides 65 extending from said magazines, type-actuators

coöoperating with said guides, and means controlled by the type for operating said actuators.

8. In a type-setter's machine, the combination with a plurality of type-magazines 70 and means for maintaining the type at a plurality of presentation-points, of guides extending from said magazines and connecting said magazines and points, type-actuators in said guides and means determined by the type demand to cause the actuators to run idly.

9. In a type-setter's machine, the combination with a plurality of type-magazines 80 and means for maintaining the type at a plurality of presentation-points, of guides extending from said magazines and connecting said magazines and points, type-actuators in said guides and means to throw said type-actuators into and out of operative position. 85

10. In a type-setter's machine, the combination with a plurality of type-magazines and means for maintaining the type at a plurality of presentation-points, of guides connecting said magazines and points and means 90 for moving the type from said magazines to said points and means to prevent the return of the type along said guides.

11. In a type-setter's machine, the combination with a plurality of type-magazines 95 and means for maintaining the type at a plurality of presentation-points, of guides connecting said magazines and points and means controlled by the presence of type in said guides for moving type from said magazines 100 to said points, said type-controlled means being provided with means to prevent the return of the type along said guides.

12. In a type-setter's machine, the combination with a plurality of type-magazines 105 and means for maintaining the type at a plurality of presentation-points, of guides extending from said magazines and connecting said magazines and points, type-actuators in said guides and spring-controlled means for 110 moving said type-actuators into operating position.

13. In a type-setter's machine, the combination with a plurality of type-magazines and means for maintaining the type at a plurality of presentation-points, of guides 115 extending from said magazines and connecting said magazines and points, type-pushers in said guides, means for actuating said pushers and means for automatically throwing said 120 actuating means into and out of operative position.

14. In a type-setter's machine, the combination with a plurality of type-magazines and means for maintaining the type at a plurality of presentation-points, of guides extending from said magazines and connecting said magazines and points, type-pushers in said guides, means for actuating said pushers and means for automatically throwing said 130

actuating means into and out of operative position, said automatic means being spring-operated into active position and operated by said pushers into inoperative position.

5 15. In a type-setter's machine, a source of type-supply, means to remove type therefrom, and type-controlled means to deflect said means from the path of the type.

16. In a type-setter's machine the combination with a plurality of approximately vertically-arranged type-magazines, of means for maintaining the type at a plurality of presentation-points at different levels in a plane inclined to said magazines, guides extending from said magazines and connecting said magazines and points and type-pushers in said guides to move the type from said magazines to said points.

17. In a type-setter's machine the combination with a plurality of approximately vertically-arranged type-magazines of means for maintaining the type at a plurality of presentation-points at different levels in a plane in-

clined to said magazines, guides extending from said magazines and connecting said magazines and points, and type-pushers in said guides, each pusher having a range of movement equal to the distance between said magazines and said presentation-points. 25

18. In a type-setter's machine the combination with a plurality of type-magazines, of means for maintaining the type at a plurality of presentation-points at different distances from said magazines, guides extending from said magazines and connecting said magazines and points, type-pushers in said guides, each pusher having a range of movement equal to the distance between said magazines and said presentation-points. 30

In testimony whereof I have signed my name to this specification in the presence of two subscribing witnesses.

JOHN G. GOSSELIN.
